(57) **CLAIM**

The ornamental design for a cable holder, as shown and described.

DESCRIPTION

FIG. 1 is a perspective view of a first embodiment of a cable holder showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of a cable holder showing my new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is bottom view thereof.

The broken line showing of a portion of the cable holder is for the purpose of illustrating environmental structure and forms no part of the claimed design. The dotted lines shown in FIGS. 8 and 11-14 define an unclaimed boundary between claimed and unclaimed subject matter.
